UNITED STATES PATENT OFFICE.

VICTOR F. RICHTER, OF PROVIDENCE, RHODE ISLAND.

DESIGN FOR A SET OF PLAYING-CARDS.

56,889.

Specification for Design.

Patented Jan. 4, 1921.

Application filed April 27, 1920. Serial No. 377,112. Term of patent 3½ years.

To all whom it may concern:

Be it known that I, VICTOR F. RICHTER, a citizen of the United States, residing at Providence, in the county of Providence and State of Rhode Island, have invented a certain new, original, and ornamental Design for a Set of Playing-Cards, of which the following is a specification, reference being had to the accompanying drawing, forming part thereof, which shows the faces of the cards employed in my new design.

I claim:—

The ornamental design for a set of playing cards, as shown.

VICTOR F. RICHTER.
